INVENTOR

UNITED STATES PATENT OFFICE.

EDWARD KELLS, OF CLEVELAND, OHIO.

DISTILLING APPARATUS.

SPECIFICATION forming part of Letters Patent No. 374,838, dated December 13, 1887.

Application filed October 30, 1886. Serial No. 217,607. (No model.)

To all whom it may concern:

Be it known that I, EDWARD KELLS, of Cleveland, in the county of Cuyahoga and State of Ohio, have invented certain new and 5 useful Improvements in Distilling Apparatus; and I do hereby declare the following to be a full, clear, and exact description of the invention, such as will enable others skilled in the art to which it pertains to make and use the 10 same.

My invention relates to improvements in distilling apparatus designed more especially for making high-fire-test products from tar or other heavy residuum had from the destructive 15 distillation of hydrocarbon oils.

Heretofore a common practice has been to treat the tar in a still, first applying a moderate heat to dispose of the moisture in the material, next to slightly increase the heat to 20 pass off the lighter products of distillation, and afterward to apply the necessary high degree of heat required to obtain the heavier grades, the different products being passed, respectively, through suitable condensing apparatus and reduced to a liquid form. Next 25 the heavier products, suitable for conversion into high-fire-test goods, were placed again in a still and reheated, first, to expel the moisture had from the exposure of the material in 30 condensation, after which the necessary high degree of heat is applied to make the desired high-test product. With such practice the expense of condensing, handling, reheating, and the waste of material thereby incurred 35 added materially to the cost of the goods.

As an improvement I have devised an apparatus consisting, essentially, of primary and secondary stills and separators, together with suitable connecting-pipes, in which the heavier 40 distillates are returned to the secondary still without material reduction in the initial heat had in leaving the primary still, to the end that a great saving is effected in time, expense, and amount of material over the processes 45 heretofore in use for this purpose.

In the accompanying drawings, Figure 1 is a side elevation of a distilling apparatus embodying my invention. Fig. 2 is an enlarged elevation in transverse section of the separator, and Fig. 3 is an enlarged view of the separator and its connections.

A and B represent the primary and secondary stills, both of which may be of ordinary construction. The primary still has one or more pipes, a, leading from the top thereof, 55 more or less in number, according to the size and construction of the still. These pipes connect with a horizontal pipe, a', the latter leading to and connecting with the separator C near the bottom of the latter. From the extreme bottom of the separator leads the pipe D, that discharges into the secondary still.

From the top of the separator leads a pipe, E, provided with a valve, e. The pipe E discharges into the condenser F, the latter being 65 of ordinary construction. The separator is made upright, as shown, and located above the line of the secondary still; and it consists, essentially, of an outside tube or shell somewhat larger in area of cross-section than the 70 tubes a or D, and provided with the necessary fitting for attaching the different pipes shown. A water-pipe, c, leads through the center of the separator, making tight joints where it passes through the head of the latter, said 75 pipe c being provided with a stop-valve, c', located above or below the separator, according as the water in the pipe c is received from above or below.

In operating the apparatus the primary still 80 is charged with tar or other similar material, and a gentle heat is applied to expel the moisture contained in such material, great care and considerable time being necessary in the operation; otherwise the pressure of steam generated inside the still from the evaporation of moisture will cause an overflow of material from the still. After the moisture is disposed of, the heat under the still is gradually increased to pass off the light product, a limited 90 amount of which is contained in the tar. The light products pass off through the separator and through the pipe E to the condenser, from which latter they are discharged in liquid form and placed in suitable containers or packages. Meantime a stream of water is passed 95 through the pipe c, for the purpose of separating any of the heavier products that might otherwise be carried off through the pipe E with the lighter product. The heavier products, containing wax, are readily precipitated by a slight reduction in temperature. Such

reduction being effected by the water in the pipe *c*, the heavier products pass out through the pipe *D* into the secondary still. As soon as the limited amount of lighter products is disposed of, the valves *c* and *e* are closed, after which the heavier products necessarily flow through the pipe *D* into the secondary still, and the supply of water in the pipe *c*, being no longer wanted, is, as aforesaid, shut off. The heat in the primary still is increased and continued till all the heavier distillates have passed off and nothing remains in the still but coke, after which the still is cooled down, cleaned out, recharged, and the process repeated. The heavier products are discharged into the secondary still while containing substantially the initial heat imparted from the primary still. Additional heat is employed in the secondary still to obtain the desired high fire-test. A tube, *b*, leads from the top of the still *B*, and is carried to a considerable elevation, from whence it may be brought down and discharged under one of the stills, if desired, or it may discharge into the open air. This tube is for the escape of gas generated in the secondary still. A tube, *B'*, leads from the top of the still *B*, through which latter tube the distillates of the secondary still pass to the condenser. From the fact that the heavier products enter the secondary still at a high temperature but little fuel comparatively is required to operate the secondary still. Also, as the material entering the secondary still is free from moisture, no time is

lost in expelling moisture, which would be 35 the case had the material been condensed. Also, the expense of handling material is saved and the waste consequent upon such handling.

What I claim is—

1. In a distilling apparatus, the combination, with primary and secondary stills, of a system of connected pipes consisting, essentially, of an escape-pipe leading from the primary still through a separator, substantially 40 as indicated, a pipe leading to the secondary still for the passage of heavier distillates, and a pipe connected to the escape-pipe for the discharge of lighter distillates, the latter being carried to a considerable elevation above the 45 said return-pipe, substantially as set forth.

2. In a distilling apparatus, the combination, with primary and secondary stills, of a separator consisting, essentially, of an upright tube or shell and a water-pipe leading through 55 the same, a pipe connecting the separator with the primary still, a pipe connecting the separator with the secondary still, and a pipe connected to the separator for discharging the lighter distillates, substantially as set forth. 60

In testimony whereof I sign this specification, in the presence of two witnesses, this 4th day of October, 1886.

EDWARD KELLS.
